UNITED STATES PATENT OFFICE.

HARRY F. KNECHT, OF WEST SALISBURY, PENNSYLVANIA.

SUPPORT FOR VEHICLE-ENGINES.

1,145,070.

Specification of Letters Patent.

Patented July 6, 1915.

Application filed January 27, 1915. Serial No. 4,699.

To all whom it may concern:

Be it known that I, HARRY F. KNECHT, a citizen of the United States, residing at West Salisbury, in the county of Somerset and State of Pennsylvania, have invented certain new and useful Improvements in Supports for Vehicle-Engines, of which the following is a specification, reference being had to the accompanying drawings.

- 10 This invention relates to supports for vehicle engines and more particularly to an auxiliary support or brace for engines of that type employed upon the Model T, Ford automobile.
- 15 The invention has for its primary object to provide a brace or support of the above character which will relieve the lower portion of the crank case from strains incident to the vibration of the engine, and thus prevent leakage of the lubricating oil.

20 It is a further object of my invention to provide an engine brace or support which, when applied, will be very rigid and substantial, and necessitates no alterations in 25 the ordinary mounting of the engine, as found in motor vehicles of the type above referred to.

With the above and other objects in view, my invention consists in the novel features 30 of construction, combination, and arrangement of parts to be hereinafter more fully described, claimed, and illustrated in the accompanying drawing, in which,

35 Figure 1 is a transverse section of the frame of a Ford automobile, showing my improved brace or support arranged in position; and Fig. 2 is a perspective view of the brace.

40 Referring in detail to the drawing, 5 designates the longitudinal side bars of the vehicle frame, and 6 designates the crank case of the engine. This crank case is provided upon the lower section thereof at opposite sides, with the hangers 7, the upper ends 45 of which are outwardly extended, as at 8, and adapted to be bolted upon the vehicle frame.

50 My improved brace is constructed of a single casting and includes a body 9 which may be of any preferred form, said body at its outer end being gradually reduced in width and formed with the arms or extensions 10. These arms are provided with cylindrical enlargements 11 which are vertically bored to receive the fastening bolts 12.

The body 9 of the brace is centrally provided in its upper portion with a recess indicated at 13 which is designed to receive the lower section of the crank case. The upper edge of the brace body, upon opposite sides of the recess 13, is disposed slightly below the plane of the upper edges of the arms or extensions 10, as indicated at 14. At the outer ends of these edge portions 14, lugs 15 are integrally formed with the brace 60 upon one side thereof and at the inner ends of the edge portions 14 and contiguous to the opening 13, are the laterally extending lugs 16 which project from the opposite face of the brace body.

70 The brace is arranged as shown in Fig. 1, with the arms or extensions thereof disposed in the channel frame bars 5 and rigidly secured in place by means of the bolts 12 which are disposed through the cylindrical enlargements 11 of said arms and the upper and lower flanges of the frame bars. The engine crank case is now disposed with its lower section in the recess 13 and the flanges of the case sections extend over the upper 75 edge portions 14 of the brace body and upon the lugs 15 and 16, said flanges being securely bolted to these lugs, as clearly shown in the drawing. The hangers 7, above referred to, which are secured upon the larger 80 portion of the crank case, have their outer ends engaged upon the frame bars 5 and securely bolted to the same in the usual manner. Thus, the crank case is very securely 85 fixed upon the brace and held against 90 all possibility of movement with relation thereto.

95 From the foregoing description, taken in connection with the accompanying drawing, it is believed that the construction and arrangement of the several parts, as well as the advantage thereof, will be clearly and fully understood.

100 My improved brace relieves the crank case and the frame of the vehicle of undue strain which would otherwise be caused by the vibration of the engine. The necessity of frequently removing the crank case for the purpose of repairing the oil can within the lower section, which is often shaken loose, 105 is also obviated by means of my invention. As the case will be kept absolutely tight at the joint between the sections thereof, escape or waste of the oil is prevented.

110 It will be noted that the invention is of

such form and construction, the same may be readily applied to the frame of the vehicle without necessitating any changes in its construction, or in the construction of 5 the engine crank case or the hangers which are provided therewith.

The brace or support may be constructed in various other forms than that shown in the drawing. It will, therefore, be understood 10 that I reserve the privilege of resorting to all such legitimate changes in the form, proportion, and arrangement of the several features of the device as may be fairly embodied within the spirit and scope 15 of the invention as claimed.

Having thus fully described my invention, what I desire to claim and secure by Letters Patent is:—

1. The combination with a vehicle frame 20 and engine crank case, of a transverse brace or support provided with arms at its ends bolted to the frame bars, said brace having a central recess in its upper edge to receive the lower section of the crank case, the flanges 25 of the crank case sections engaging upon the upper edge of the brace upon opposite sides

of the recess, and lugs formed upon the brace body to which said flanges are bolted.

2. The combination with a vehicle frame 30 and crank case provided upon its lower section at opposite sides with hangers, of a transverse brace having arms formed upon its ends bolted to the longitudinal frame bars, said brace being also provided with a central recess in its upper portion to receive the lower section of the crank case, and spaced lugs projecting from the opposite faces of the brace at its upper edge and on opposite sides of said recess, the joint flanges 35 of the crank case extending over said lugs and being bolted thereto, the outer ends of the hangers resting upon the outer ends of the longitudinal frame bars in spaced relation to the arms of the brace and being 40 bolted to said bars.

In testimony whereof I hereunto affix my signature in the presence of two witnesses.

HARRY F. KNECHT.
